UNITED STATES PATENT OFFICE.

ALBERT L. HIGGINS, OF BAR HARBOR, MAINE.

FIGURE WHEELED TOY.

Application filed January 7, 1927. Serial No. 159,646.

This invention relates to a figure wheeled toy, one of the objects being to provide a toy the bottom portion of which supports members mounted for lateral swinging, means 5 being provided for setting up lateral tilting of the toy so that as it moves forwardly the swinging members will be oscillated laterally.

A further object is to provide a toy of 10 this character which is cheap to manufacture and the movable portions of which are provided with bearings whereby they can be caused to swing freely during the lateral tilting of the structure as it moves forward.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the accompanying drawings, the preferred form of the invention has been shown.

In said drawings,

Figure 1 is a side elevation of a figure toy embodying the present improvements, portions being broken away and the axle being shown in section.

Figure 2 is a top plan view.

Figure 3 is an end elevation of a portion 35 of the toy.

Figure 4 is a plan view on a reduced scale of a portion of a modified form of toy.

Referring to the figures by characters of reference 1 designates a block constituting 40 the body of the toy, the same being provided along its lower surface with a central longitudinal strip 2 in which is journaled an axle 3, this axle being located adjacent the rear end of the strip 2. To the ends of the 45 axle are secured eccentric wheels 4, the long radius of one wheel being extended oppositely to the long radius of the other wheel. Thus as the toy is pulled forwardly the two wheels will cooperate to tilt the body 1 laterally from one side to the other. Spacing sleeves 5 or the like can be mounted on the axle between the strip 2 and the wheels. Or, if preferred, the axle can be reduced in diameter at the center where it is journaled in 55 the strip 2.

The front end portion of the toy can be

supported in any suitable manner. For example a narrow strip 6 can be secured along the center of the front portion of the strip 2 so as to constitute a runner for gliding over the supporting surface. A cord used for pulling the toy can be attached to the front end of the strip 2. Such a cord has been indicated at 7.

Various movable devices can be mounted 65 on the block 1 for simulating different articles. In the structure illustrated the toy represents a boat having a sail and a crew. The sail is formed of a separate member 8, preferably a thin piece of wood, and a nail 70 9 is driven into the lower edge of the member near the front thereof. This nail is also extended through a sleeve 10 which is seated in a bore 11 extending through the block 1 and the strip 2. The head 12 of the nail 75 is located under the lower end of the sleeve 11 and is supported by the head of a tack 13 which is driven into the strip 6, this strip serving to close the lower end of the bore 11. By providing a bearing such as 80 described the member 8 can swing freely from one side to the other and this swinging movement can be limited by stop pegs 14 which can be shaped to simulate sailors.

Another movable member can be located 85 back of the member 8. In the structure shown in Figure 1 this movable member, indicated generally at 15, can simulate the captain of the boat. Figure 15 has an extension 16 at the back thereof for receiving the 90 point of a nail 17 driven upwardly and rotatable freely in the strip 2 and the block 1. Stop pins 18 can be located adjacent the sides of the block 1 for limiting the lateral swinging of the member 15.

Obviously instead of having members shaped as shown in Figure 1, other shapes can be employed. For example two or more cut-outs simulating sails, ducks, or the like, can be mounted on the block. In Figure 4 100 has been shown a block 19 corresponding with the block 1 on which three sails 20, 21 and 22 are mounted to swing about the pivots 23 consisting of nails driven upwardly into the members 20, 21 and 22 and rotatable 105 freely in the block 19 as illustrated in Figure 1. The member 20 extends between the members 21 and 22 and when the block is tilted laterally, this member 20 will strike one of the members 21 and 22, causing a smacking 110 sound. Lateral swinging of the members is of course limited by stops 24. As the toy

is moved forwardly the members will swing toward one side, as indicated by full lines and toward the other side as indicated by dotted lines in Figure 4, a noise being produced at the completion of each swinging movement by the violent contact of the members with each other.

The structure shown in Figure 4 is of course provided with eccentric wheels such as shown in connection with the device illustrated in Figures 1, 2 and 3 and the bearings for the oscillating members are also the same as those in Figure 1. As the front end of the runner 6 contacts with the smooth supporting surface, it will be seen that the toy can be pulled by a flexible cord. The point of contact between the runner and the supporting surface constitutes the fulcrum on which the toy will be rocked as it moves forwardly, this rocking action being set up by the eccentric wheels 4. As the boat is rocked, thereby simulating the motion of a small boat at sea, the movable members carried by the block 1 will swing laterally and come against stops in the paths thereof, thereby producing a noise which renders the toy especially attractive to small children. In the modified structure shown in Figure 4 a clapping noise will be produced by the sails 20 striking against the members 21 and 22 and by these latter members striking against stops in the paths thereof.

What is claimed is:

1. A figure wheeled toy including a body, a runner at the front end thereof for sliding contact with a supporting surface, a pull cord connected to the front end of the body,

40 oppositely mounted eccentric wheels supporting the rear end of the body constituting means, when rotated, for imparting a tilting movement to the body in all directions, said body, when tilted, moving about the point of contact between the runner and the supporting surface, members supported by the body and mounted to swing freely about an axis extending upwardly from the body, said body, when tilted by the wheels, constituting means for oscillating the members, and means on the body cooperating with the members for limiting the movement of the members and producing a noise.

2. A figure wheeled toy including a body, a runner at the front end thereof for sliding contact with a supporting surface, a pull cord connected to the front end of the body oppositely mounted eccentric wheels supporting the rear end of the body constituting means, when rotated, for imparting a tilting movement to the body in all directions, said body, when tilted, moving about the point of contact between the runner and the supporting surface, members supported by the body and mounted to swing freely about an axis extending upwardly from the body, said body, when tilted by the wheels, constituting means for oscillating the members, and means on the body cooperating with the members for limiting the movement of the members and producing a noise, one of said members depending between the other members.

60 In testimony that I claim the foregoing as my own, I have hereto affixed my signature.

ALBERT L. HIGGINS.
